UNITED STATES PATENT OFFICE.

WALTER T. FLING, OF ST. JOSEPH, MISSOURI.

BURNER.

No. 895,999.

Specification of Letters Patent.

Patented Aug. 11, 1908.

Application filed September 26, 1907. Serial No. 394,762.

To all whom it may concern:

Be it known that I, WALTER T. FLING, a citizen of the United States, residing at St. Joseph, in the county of Buchanan and State 5 of Missouri, have invented new and useful Improvements in Burners, of which the following is a specification.

This invention relates to natural gas burners, and one of the principal objects of the 10 same is to provide a bell shaped deflector for the burner which will deflect the heat radially from the center of the burner.

Another object is to provide a gas burner comprising a heating chamber having a per- 15 forated top, a series of radial ribs and a bell- like deflector secured to the top for radiating the heat developed by the burner.

These and other objects may be attained by means of the construction illustrated in 20 the accompanying drawing in which

Figure 1 is a central vertical section taken through a gas burner made in accordance with my invention. Fig. 2 is a plan view of the burner with the bell-shaped deflector re- 25 moved.

Referring to the drawing for a more specific description of my invention, the numeral 1 designates the base of the burner which, as shown, is circular in form and provided with 30 a central boss 2 provided with a screw threaded opening 3 therein which communicates with the interior of the burner. An annular rib 4 is formed upon the upper side of the base 1 so that a shoulder 5 is formed, 35 said shoulder extending from the rib 4 to the periphery of the base.

The upper member of the burner comprises a circular upper wall 6 provided with a series of radially disposed heat retaining ribs 7 and

between the ribs 7 a series of perforations 8 40 are provided, said perforations forming gas jets. Formed centrally upon the upper member 6 is an annular seat 9 for the bell-shaped deflector 10, said deflector being secured upon the upper member 6 by means of 45 a bolt 11 passing through the aperture 12 in the upper member 6 and through the bottom 13 of the bell. The upper member 6 is provided with an annular flange 14, the lower edge of which is seated upon the shoulder 5 50 outside the rib 4, thus forming a heating chamber 15 between the base 1 and the upper inner wall of the upper member 6.

From the foregoing it will be obvious that the heat developed by the burner is deflected 55 outwardly by the bell 10. My invention is of simple construction, is composed of few parts, can be manufactured at slight cost and is very reliable and efficient in use.

Having thus fully described the invention 60 what is claimed as new is:

The herein described gas burner comprising a base member having an annular shoulder and a rib adjacent said shoulder, an upper member having a flange seated on the 65 shoulder of the base member, said upper member having a series of radially disposed ribs upon its outer face and perforations between the ribs, and a bell-shaped deflector secured to the upper member and having up- 70 wardly, outwardly inclined walls.

In testimony whereof I affix my signature in presence of two witnesses.

WALTER T. FLING.
